UNITED STATES PATENT OFFICE.

VAUGHN R. PHELPS, OF AKRON, OHIO.

FABRIC-STOCK SHELL.

1,357,345.

Specification of Letters Patent. Patented Nov. 2, 1920.

Application filed December 11, 1919. Serial No. 344,110.

To all whom it may concern:

Be it known that I, VAUGHN R. PHELPS, a citizen of the United States, residing at Akron, in the county of Summit and State 5 of Ohio, have invented certain new and useful Improvements in Fabric-Stock Shells, of which the following is a specification.

The invention has for an object to effect improvements in the construction of stock 10 shells used for the winding of fabric stock in various textile and other manufactures, and its present embodiment is especially useful in the rubber industry where the stock fabric must be frictioned and skim- 15 coated, which requires the fabric to be wound upon a stock shell prior to passage through a calender train.

In the handling of this fabric, it is easily 20 damaged by contact with angular edges or protuberances, and stock shells as heretofore constructed have been unsatisfactory because it has not been practicable to produce them in a manner to obviate angularities or the development of protuberances, 25 such as loose rivets, rough castings, or blow holes in the castings, or other causes. It is therefore an object of my invention to eliminate the necessity for using rivets, bolts or screws in the shell portion proper, in order 30 to securely mount it upon supporting structure. A further aim is to give an improvement in the internal construction of the shell calculated to facilitate its manufacture and also its use.

35 Additional objects, advantages and features of invention will appear from the construction, arrangement and combination of parts as indicated in the following description, and in the drawings, wherein,

40 Figure 1 is a longitudinal sectional view of a shell constructed in accordance with my invention, with its interior structure partly in elevation,

Fig. 2 is an elevation of the inner side of 45 one of the end castings,

Fig. 3 is a similar view of one of the intermediate castings,

Fig. 4 is an elevational view of the shell complete.

50 There is illustrated a shell comprising a cylinder 10 which may be of seamless tubing, or other suitable sheet material, within which there are located in the present instance, two intermediate rings 11 fitted 55 tightly in the cylinder so that they may be

frictionally held therein, although if desired they may be secured therein by any approved method. Set in each end of the cylinder, there is an end casting 12, the casting at each end being the same in structure. 60 The castings 12 correspond in diameter to the rings 11 and are similarly fitted in the cylinder 10. The castings 12 are formed with a central body portion set inwardly a distance to form a circular recess 13 in the outer side of each, and an outside rabbet 14 is formed around the casting into which a projecting end portion of the cylinder 10 is peened upset or spun so as to fit snugly in the rabbet and flush with the outer end face 70 of the casting 12, as at 15. The rings 11 and castings 12 are formed with rectangular hubs 16 and 17 respectively, the hubs of the rings projecting a distance each way longitudinally of the shell, while the hub 17 75 projects inwardly from the body portions 18 of the castings. The body 18 of the castings 12 is formed with a plurality of openings 19 by which ingress and egress of air or gas is permitted. The hubs 16 are connected to the rings 11 by radial arms 11'. The hubs above mentioned are each provided with a square opening therethrough, the openings 20 through the rings 11 receiving snugly a square tube 21, while the openings 80 22 through the bodies of the castings 12 are of the same size as the clear way through the tube 21 and alined therewith. The hubs 17 are formed with larger square recesses 85 therein, however, receiving the respective ends of the tube 21 snugly, so that when the ends of the shell are peened or spun inwardly into the rabbeted portion of the end castings 12, these are borne tightly against the tube 21 and the parts thus tightly held in coengagement without liability of loose play or rattle. The castings 12 each have an inwardly projecting lug 24 integrally formed thereon with an outer planiform face parallel to the cylinder 10 and spaced 90 slightly inward thereof, these lugs being disposed in alinement when the parts are assembled. The cylinder 10 is formed with a longitudinal slot 25, in line with these lugs, its opposite ends extending a distance outwardly over the lugs, so that the outer faces of the lugs are exposed to the slot. The lugs are suitably drilled and tapped to receive screws 26 by which a mounting strip 95 27 is secured thereto, lying longitudinally 100 110

within the slot 25. As shown the strip 27 is also set in suitable recesses 28 alined therewith and formed in the rings 11.

In use, the shell is mounted in a machine by having inserted therethrough a rectangular bar, the tube 21 serving to guide the bar readily through the shell and afford a suitable mounting by which the shell may be rotated and supported. One or both of the screws 26 may be loosened and the strip 27 raised to permit the insertion of one end of an apron 30 customarily employed as a first wrapping upon the shell as indicated in Fig. 4, after which, the screws being tightened, the apron is securely held in adjusted position.

The strip 27 may have its exterior surface set slightly below that of the adjacent portion of the shell 10, or flush therewith, as found desirable.

It will be seen that a very light construction in a shell is provided which is yet adequately rigid, and is quite durable and efficient in use. It is adapted to be assembled with a minimum of labor, and the parts produced by customary practices well understood in the art.

What is claimed:

1. A stock shell comprising an exterior cylinder an intermediate cylindrical reinforcing element snugly fitted therein, and end members tightly fitted therein, and peripherally rabbeted at their outer parts, the end portions of the cylinder being turned into the rabbet and finished flush with the end face of the end members.

2. A stock shell comprising a cylinder of metal an intermediate reinforcing member therein having an opening therethrough, end members snugly fitted in the cylinders having recesses at their inner sides corresponding to the opening in the said reinforcing member, a tube set snugly in the reinforcing member and said recesses, the end members having openings therethrough alined with the openings in the tube, the end members being peripherally rabbeted, and the ends of said cylinder being turned into the rabbet as and for the purposes described.

3. A stock shell comprising a longitudinally slotted cylinder, an intermediate reinforcing member snugly fitted therein, end members snugly fitted in respective ends of the cylinder and formed with parts projected beneath respective ends of the slots of the cylinder, a strip removably set in the slot upon said end members, and means to secure the strip therein for the purposes described.

4. A stock shell comprising a facing cylinder, an intermediate reinforcing cylinder snugly fitted therein and having a hub provided with an angular opening, end reinforcing cylinders snugly fitted in the facing cylinder and having hubs formed with angular recesses on their inner sides, alined with the opening of the first named hub and having smaller angular openings therethrough and a tube snugly fitted in the first hub with its ends engaged snugly in said recesses.

5. A stock shell comprising a facing cylinder, an intermediate reinforcing cylinder snugly fitted therein and having a centrally apertured hub, end reinforcing cylinders snugly fitted in the facing cylinder and having hubs formed with recesses on their inner sides of the same size and alined with the aperture of the first named hub, the end reinforcing cylinders having small central openings therethrough, a tube fitted in the intermediate reinforcing element snugly, and having its ends set in said recesses, the inner diameter of the tube being the same as said smaller opening through the end reinforcing members, said end reinforcing members having peripheral rabbets at their outer part of a depth longitudinally of the device corresponding to the thickness of metal in said facing cylinder, the end edge portions of said facing cylinder being peened or otherwise turned into said rabbets to compress said end reinforcing members against said tube and hold the parts securely in operative relation.

6. A stock shell comprising a cylindrical tube of metal, reinforcing means snugly set therein including end members having portions engaged in the cylinder and spaced a distance inwardly of the end of the cylinder, projecting end portions of the cylinder being peened and turned inwardly against the reinforcing part as and for the purposes described.

7. In a structure of the character described a facing cylinder, cylindrical reinforcing members set therein, and a member interposed between the reinforcing members, in snug abutment therewith, said reinforcing members being peripherally rabbeted at their outer parts, and the extremity of the cylinder being turned into the rabbet, whereby the parts are secured in operative relation.

In testimony whereof I have affixed my signature in presence of two witnesses.

VAUGHN R. PHELPS.
